UNITED STATES PATENT OFFICE.

WALENTY J. MALECKI, OF EAST PITTSBURGH, PENNSYLVANIA.

RATCHET-SCREWDRIVER.

1,384,032.

Specification of Letters Patent. Patented July 5, 1921.

Application filed June 23, 1920. Serial No. 391,239.

To all whom it may concern:

Be it known that I, WALENTY J. MALECKI, a citizen of the United States, residing at East Pittsburgh, in the county of Allegheny and State of Pennsylvania, have invented a new Ratchet-Screwdriver, of which the following is a specification.

My idea was to create a tool, which could be used not only as an ordinary screw driver, but also, which could form a screw driver and lever-arm in one tool.

I attain this arrangement by the mechanism illustrated in the accompanying drawing, in which—

15 Figure 1 is a side elevation of the screw driver assembled for ordinary use.

Fig. 2 is a side view of the handle arranged at an angle to the rod representing a screw driver and lever-arm in one tool.

20 Fig. 3 is a horizontal section through the head of the handle, showing the arrangement of one ratchet—another and reversed ratchet being similar and combined from similar parts, is not shown.

25 Fig. 4 is an upper view of the handle bottom piece, and bulb-trap, with the upper plate off, showing how the bulb-trap is combined.

Fig. 5 is an axial section of the bottom-30 piece of the handle, showing one side of the bulb-trap.

Fig. 6 is an axial section of the handle-head, along the vertical slot and hole.

Fig. 7 is a section throughout the ratchet 35 mechanism, omitting the pawls representing the arrangement of key.

Fig. 8 is a side view of the key.

Similar numerals refer to the similar parts throughout the several views

40 The handle middle-piece 1, which is a sleeve having a reduced bore at one end forming a rod bearing 2, the bottom-piece 3, and the head 4, attached to each other by threads form the handle of the tool, inside 45 of which may be slid the rod 5, flattened at its upper end, to form a screw driver blade, and provided with a bulb on its other end to fit the bulb trap shown in Fig. 4, and with a key slot, along one side of its length.

50 The bulb-trap, mounted in bottom-piece 3, which is formed like a cup for this purpose, consists of two pivoted arms 7, a spring 8 for each arm, an inclosing ring 9, all arranged between two plates 10 connected together by two rivets 11, 11 forming the pivots for the arms and screwed into the bottom-

piece as shown in Fig. 2, and said bulb-trap supports the rod 5 holding it by the bulb.

The arms 7 are hollowed on their insides and finished, so the bulb can be easily pushed 60 in, or pulled out, when the other adjustment is required.

The rod 5 has a ratchet mechanism, mounted in handle-head 4, which consists of four pawls 12, (two on each side), four 65 springs 13, actuating the free ends of the pawls 12, two ratchet wheels 14, the hubs of which are inserted into the opening of the middle piece 15, with the ratchet wheels on the outside.

70 The springs 13, are cut out from two pieces of flat steel and bent to the required form, each providing two springs, as shown in Fig. 6.

The middle-piece 15, is provided with flat 75 bottomed recesses or seats on its two opposite sides, for reception of the springs.

The springs 13 and their seats are provided with holes for reception of threaded pins 19, which being screwed into the 80 middle-piece 15, retain the springs 13 in their positions by the shoulders and also support the ratchet mechanism, by their extended ends, in the openings of the handle-head 4.

85 All these parts are mounted between two plates 16, connected by two rivets 18, constituting the pivots for the pawls 12 and compose the ratchet mechanism operable by the handle 1, when arranged either axially 90 of rod 5 or as lever-arm (as in Fig. 2). In order to adjust the ratchet mechanism to be rotated either to the right or to the left a key 6 is provided which fits slidably in the key slot or groove in rod 5 and has a reduced 95 portion which does not project outside of said groove, a rib at one end inserted in a similar hole of the ring by which it may be engaged to slide it and a wider portion which forms the operative part and may be slid into engagement alternatively with either of the ratchet wheels to key said wheel to rod 5; it being understood, of course, that the teeth of and pawls for said wheels operate in opposite directions as indicated in 105 Fig. 6.

100 In assembling the mechanical screwdriver for ordinary use, shown in Fig. 1, I put the key 6 into the groove to the inside of the mechanism first, then push the rod 5 fitting its keyway with the key, into the handle of tool until its bulb engages the

bulb holder in the bottom piece of the handle.

To adjust the screw-driver, as shown in Fig. 2, I pull the rod 5 out of the bulb-trap 5 and through the head 4 sufficiently for it and the ratchet mechanism to be given a quarter turn in the slot of the handle-head and put it into the hole, provided for this purpose in opposite side of the handle-head 10 4 from the slot. Next, disconnecting the bottom-piece 3 from handle-piece 1, I attach it to the bulb of the rod, by the trap previously described. In this way I obtain a mechanical screw-driver in which the handle 15 has a ratchet connection with the blade either in alinement therewith or as a lever arm.

The handle head is prevented from unscrewing from the intermediate sleeve by a 20 latch 20 engaging a notch.

I claim:

1. The handle of the mechanical screw-driver, consisting of the handle-middle-piece with a rod bearing inside of its lower 25 end, also threaded on its lower end for receiving the handle bottom-piece, threaded on its upper end to receive the head of the handle, with catch and notch between them, preventing the two parts from screwing off, 30 with vertical slot and hole on opposite side of the head of the handle for receiving the rod, transversely of or in alinement with the handle, a pivotal member in which the rod can slide and two bearings in the opposite 35 sides of the handle-head to support the adjusting mechanism, as shown and described.

2. A screw-driver ratchet mechanism, consisting of two toothed and hubbed wheels having their hubs inserted in an opening of a middle-piece, four pawls engaging the 40 toothed wheels, four springs (from two pieces of flat steel) retaining the pawls in engagement, two side plates fastened by two rivets, passing through the pawls and middle-piece, which is provided with recessed 45 seats at two opposite places for receiving the springs, which are provided with holes and are fastened by means of pins having threads for screwing into holes of the middle-piece, and shoulders for retaining the 50 springs and fitting into bearings in the head of the handle, by which the ratchet mechanism is pivotally supported to permit it to shift into position in alinement with or at an angle to the handle. 55

3. A bulb-trap consisting of two arms, for receiving the bulb, two springs retaining the arms, in engagement with the bulb and a ring surrounding and securing the flat springs in their positions, all being mounted 60 between two plates, provided with circular openings at their centers, and secured by two pins, driven into the handle-bottom-piece, and forming a bulb-trap supporting the rod of a screw-driver. 65

In testimony of this, I affix my signature in the presence of two witnesses.

WALENTY J. MALECKI.
